UNITED STATES PATENT OFFICE

123,556

DESIGN FOR A WALLPAPER

Ruth Schuessler, Chicago, Ill.

Application October 9, 1940, Serial No. 95,698

Term of patent 3½ years

To all whom it may concern:

Be it known that I, Ruth Schuessler, a citizen of the United States of America, residing in Chicago, county of Cook, and State of Illinois, have invented a new, original, and ornamental Design for a Wallpaper, of which the following is a specification, reference being had to the accompanying drawing, forming part thereof, wherein, the figure of the drawing is a plan view of a wallpaper showing my design.

I claim:

The ornamental design for a wallpaper, substantially as shown.

RUTH SCHUESSLER.
